United States Patent Office.

JOHN GOURLAY, OF ESCANABA, MICHIGAN.

Letters Patent No. 77,480, dated May 5, 1868.

IMPROVEMENT IN PORTABLE BATH-HOUSES.

The Schedule referred to in these Letters Patent and making part of the same.

TO ALL WHOM IT MAY CONCERN:

Be it known that I, JOHN GOURLAY, of Escanaba, in the county of Delta, in the State of Michigan, have invented a useful and improved Portable Bath-House; and I do hereby declare that the following is a full and exact description thereof, reference being had to the accompanying drawings, and to the letters of reference marked thereon, making a part of this specification, in which—

Figure 1 is an elevation of my bath-house, with the upper door open.

Figure 2, a section of the same, taken through the red line X' X', fig. 3.

Figure 3 a plan view, with one corner broken away to give a clear view of the construction of the outside covering.

The nature of my invention relates to a bath-house, which can be readily taken apart, and removed from one room to another, and put together for use by any person of ordinary skill, without the use of tools; and further, in the use of an adjustable water-tank, made to run in slides, and suspended upon a cord, and arranged to be lowered down for the reception of water, and raised up to the proper height for discharging the same upon a person in the house.

And in arranging a gate with a jointed lever and a crank, by means of which the flow of water from the tank can be readily controlled. Also, in the use of double doors for the convenience of bathing children without wetting the clothes of a person who has them in charge, as the lower door can be shut and yet allow sufficient room to perform the operation.

In order to give a correct understanding of my invention, I have marked corresponding parts with similar letters, and will now give a detailed description.

C represents the sides and ends of the bath-house, which are made of any suitable lumber, matched together or otherwise, as most convenient for making the house the required size. A substantial bottom, A B, is also made of wood and framed closely together, so as to be water-tight, and has a rabbet, a, made in its inner upper corner for supporting the sides and ends C C C C, and the corner posts D D D D, as seen at figs. 1 and 2. The corner posts have also rabbets, as seen at fig. 3, for supporting the edges of the ends and sides, C C C C, and are fitted at their tops to receive a cap, E, which holds the sides and ends of the house together, said cap being arranged so as to be lifted off from the top of the house when it is to be taken apart.

Wooden slides, H H, are rigidly attached to one end of the house, and have tongues on their inner sides for guiding the tank, I, when being run up and down.

This tank is supported by a cord, U, which is fastened to one of the slides H near its top, and made to pass under pulleys K K, and over a pulley, J, and brought down and fastened to a drum, X, fig. 2, which may be operated by a crank, S, and held in place by a ratchet, T, and loop, V.

The arrangement for regulating the flow of water is as follows:

A gate, M, is arranged to slide in a guide, Y, and has a lever, n, jointed to it and to a crank, P, having a bearing in a block, L, and can be raised to give a required flow of water through a perforated plate, R, by simply elevating the end of crank P, as shown at fig. B B.

The doors F G are hung so as to open separately, and for the purpose above set forth.

Having thus described my device, what I claim, and desire to secure by Letters Patent, is—

The general combination and arrangement of the tank I, slides H H, pulleys K K, J, cord U, drum X, gate M, lever n, crank P, with house A B C D E F G, substantially as set forth.

JOHN GOURLAY.
